4 Claims. (Cl. 260—268)

1

This invention relates to new organic compounds. More particularly, it relates to 1-piperazyl-4-methylthioxanthones and their method of preparation.

The compounds of the present invention may be illustrated by the following structural formula:

in which R is a member of the group consisting of hydrogen and methyl radicals.

These compounds are solids having a definite melting point and are soluble in aqueous acid solution and, in general, in organic solvents.

The compounds of the present invention are prepared by reacting an isomeric mixture of 1-chloro-4-methylthioxanthone and 4-chloro-1-methylthioxanthone with an alkylated or carboxalkylated piperazine. The isomeric mixture is used as starting material since it is commercially available. The two isomers are, for practical purposes, inseparable and there is an indica-

5 The reaction is preferably carried out in a hydrocarbon solvent such as toluene, benzene, xylene, and the like. A desirable method is one in which the intermediates are heated in a solvent at refluxing temperatures for a period of from 4 to 24 hours. In general the preferred temperature may be from 50° to 150° C.

10 The products of the present invention are active against schistosomiasis. The activity of the compounds is determined by inoculating mice intraperitoneally with a suspension of viable cercariae and allowing 6 to 8 weeks for the development of adult worms in the mesenteric and portal veins or liver. Treatment is started when 15 adult worms are present and is continued for various periods of time thereafter. The effect of the treatment on the schistosomes is determined by killing the mice, necropsy and counting the number of living and dead worms in the mesentery or liver. In untreated mice about 90% of the worms are found in the mesentery and dead worms are seldom found in the liver. Schistosomacidal compounds cause a pronounced shift of worms from the mesentery to the liver and within a short period of time most of the worms in the liver are dead. The following table 20 shows the results obtained using the compound 25 and within a short period of time most of the worms in the liver are dead. The following table shows the results obtained using the compound 1-[1'-(4'-methylpiperazyl)-4-methylthioxanthone against *Schistosoma mansoni*:

Activity of 1-[1'-(4'-methylpiperazyl)-4-methylthioxanthone against *Schistosoma mansoni* in mice

Ip. = Intrapерitoneally.
B. I. D. = Twice a day.

tion they may be chemically linked together in some manner. The 4-chloro isomer is less reactive than the 1-chloro compound and under the conditions of the present process, does not combine with the alkylated or carboxalkylated piperazine. The unreacted 4-chloro compound, lacking basic properties, is not extracted when using an aqueous acid solution. The desired product, on the other hand, is basic and is extracted by the aqueous acid solution and subsequently precipitated by neutralization with an alkaline substance.

50 The compounds of the present invention are toxic to the agents causing schistosomiasis while being relatively non-toxic to the host. The compounds also are more active and less toxic than antimonial compounds such as tartar emetic.

55 The compounds of the present invention may be prepared by the following method which illustrates the preparation of 1-[1'-(4'-methylpiperazyl)-4-methylthioxanthone.

An isomeric mixture of 20 g. of 1-chloro-4-methylthioxanthone and its isomer 4-chloro-1-methylthioxanthone, 10 g. of sodium bicarbonate,

20 ml. of 1-methylpiperazine and 250 ml. of xylene was refluxed for 16 hours. The xylene was decanted off and washed with water. The product was then extracted with aqueous hydrochloric acid and poured into an iced aqueous ammonia mixture. The resulting precipitate was filtered off, washed with water and dried. A yield of 11 g. of 1-[1'(4'-methylpiperazyl)]-4-methylthioxanthone, having a melting point of 133°-134° C. was obtained.

The compound 1-(1'-piperazyl)-4-methylthioxanthone can be prepared by the same process illustrated above with the exception that a carbalkoxy piperazine, such as carbethoxy-piperazine, is used instead of 1-methylpiperazine and the carbalkoxy or carbethoxy group removed by acid hydrolysis.

I claim:

1. Compounds having the general formula:

in which R is a member of the group consisting of hydrogen and methyl radicals.

2. 1-[1'(4'-methylpiperazyl)]-4-methylthioxanthone.

3. A method of preparing compounds having the general formula:

5

in which R is a member of the group consisting of hydrogen and methyl radicals which comprises reacting 1-chloro-4-methylthioxanthone with a member of the group consisting of carboxalkylated piperazines and N-methylpiperazine in a hydrocarbon solvent and recovering said product therefrom.

15 20 25 4. A method of preparing 1-[1'(4'-methylpiperazyl)]-4-methylthioxanthone which comprises reacting 1-chloro-4-methylthioxanthone with 1-methylpiperazine in a hydrocarbon solvent and recovering said product therefrom.

SAMUEL KUSHNER.
